poration of Massachusetts

Application January 6, 1944, Serial No. 517,247

9 Claims. (Cl. 66—107)

This invention relates to knitting machines and methods of knitting and more particularly to knitting machines having two feeds each of which feeds a yarn or yarns to the needles during the knitting of heels, toes or other reciprocatory knitting.

In the knitting of heels and toes, or during other reciprocatory knitting on machines of the type described, it is found, particularly on fine gauge machines, that the sinker between the last active needle and the first inactive needle tends to trap the yarn fed at the first yarn feed against the first inactive needle and shear the yarn. It is an object of this invention to provide, in a machine of the type described, such a relation of the needles and sinkers and control of the movements thereof as to relieve the strain on the yarns and prevent the shearing thereof.

In the drawings:

Fig. 1 is a diagrammatic plan view illustrating the feeding of two yarns to the needles during reciprocatory knitting in a rotary needle cylinder hosiery knitting machine;

Fig. 2 is a fragmentary diagrammatic view in elevation of a portion of a machine such as is shown in Fig. 1, the spacing of the needles being increased for clarity of illustration;

Fig. 3 is a view in perspective showing a few needles and associated sinkers in accordance with this invention, their direction of rotation being indicated by the arrow;

Fig. 4 is a fragmentary plan view of a sinker cap and sinkers corresponding to Fig. 3, a portion of the sinker cap plate being broken away, the direction of the movement of the sinkers with respect to the sinker cap being indicated by the arrow;

Fig. 5 is a view in elevation showing the first inactive needle of Fig. 3 and the sinker in advance thereof, the sinker being shown in full lines in its advanced or knocking over position and in broken lines in its retracted position; and

Fig. 6 is a fragmentary view illustrating the knocking of a stitch over the top of the last active needle in the knitting of a course of a heel or toe by reciprocatory knitting.

In the drawings there are shown the independent needles N of a circular knitting machine, the needles being mounted in the usual grooves or tracks of a needle cylinder (not shown) and operated to knit yarn taken at each of two yarn feeds by the knitting cams 357, 360, 361, 10 and 11, and the cam ring 271. There are also shown the sinkers S mounted in the usual sinker head (not shown) and operated between adjacent needles

by means of butts 13 engaging in the cam path 14 between the cams 16 and 17 in the sinker cam cap 300. The needles shown have their upper or hook ends bent forward sufficiently that the back portion or casting off point 26 of the hook 25 of each needle is in line with or in advance of the forward edge 27 of the needle shank as indicated by the dot and dash line in Fig. 5. For convenience, a group of the needles N, positioned to clearly illustrate the invention, have been designated by the characters 1, 2, 3, 4, 5 and 6, respectively, and the associated sinkers have been designated 1', 2', 3', 4', 5', and 6' respectively.

Separate-course yarns Y and Y' are fed to the needles during reciprocatory knitting of heels and toes from spaced yarn guides, the yarn Y being fed, as shown in Fig. 1, by the yarn guide 19 at the throat plate 20 while the yarn Y' is fed by the yarn guide 21 at the throat plate 22. During rotation of the needles counterclockwise, as shown in Fig. 1, the yarn Y is knit first and then yarn Y', both yarns passing to the needles from the left hand corners of their throat plates. Upon reversal of the rotation of the needles, the yarn Y' is knit first and then yarn Y, both yarns passing through the right hand corners of their throat plates and two courses being knit during the rotation of the needle cylinder in each direction.

As each rotary movement of the needle cylinder during reciprocatory knitting is of sufficient extent to carry all the needles active in the knitting of the heel and toe past both yarn feeds, the yarn fed at the first yarn feed, during each rotary movement extends, as shown in Figs. 1 and 2, from its yarn feed past the second yarn feed to the loop knit by the last active needle during that movement. This causes the first knit yarn to extend from the last active needle at a very small angle above a horizontal plane passing through the throats 24 of the sinkers and, in consequence thereof, the first knit yarn is engaged beneath the nebs 23 of the sinkers associated with a number of the inactive needles, sinkers 3', 4' and 5' being shown so engaging the first knit yarn in Fig. 3. As the sinkers travel in the cam path 14 between the cams 16 and 17, they are moved inwardly by the cam 17 until they reach the limit of their inward movement at the point 18 which corresponds to the position in which the adjacent needle casts off its loop. However, as the inactive needles are not drawn down, the sinkers following the last active needle in the knitting of a course, as sinkers 2', 3', 4' and 5', tend to trap the first knit yarn against the shanks of the

adjacent needles as they are moved forward by their movement along the cam 17 to the knocking-over point at 18. In coarse gauge machines, there is sufficient clearance between the sinkers and needles and sufficient strength in the yarns to permit of the yarn easing the strain therein by drawing yarn from the yarn feed. In the finer gauge machines, the clearance between sinkers and needles is so much closer there is more of a shearing action as the sinker 2' associated with the last active needle 2 is moved to the knocking over point. The first knit yarn having passed under the nebs of a number of succeeding sinkers, as sinkers 3', 4' and 5' of Fig. 3, is trapped against the shanks of the inactive needles so that the drawing of any yarn from the yarn guide is rendered difficult and the yarn is frequently severed or broken.

To effect the knocking over of a stitch it is necessary that the sinker following the needle drawing the loop be advanced to a point such that the sinker throat will be to the rear of the needle hook so that the cast off loop will be drawn to the rear of the needle. However, it is found, as just described above, that if the sinkers following the first few inactive needles are advanced so that the throats 24 thereof are beyond the forward edges 21 of the needle shanks, the first knit yarn is trapped so yarn cannot be readily drawn from the yarn feed and the yarn is frequently sheared by the sinker 2' following the last active needle 2.

It is necessary, therefore, in order that the first knit yarn shall not be cut to restrict the movements of the sinkers with respect to the shanks of the inactive needles while having the sinkers advanced sufficiently to knock over the loops. This result has been attained by using needles having the hooks thereof bent forward to such an extent that the upward projection of the forward edge 27 of the needle shank, as shown by the dot and dash line in Fig. 5, will pass in back of the hook 25, preferably passing through the knocking-over point 26 in the back of the hook 25. The point to which the sinker can be advanced may be varied to some extent by changing the width of the needle shank; this advance however, is limited by the necessity for strength in the needle shank. As shown in Fig. 6, the throat 24 of the sinker is advanced far enough to insure the last knit loop 28 of the first fed yarn being carried past the knocking over point 26 on the needle hook while, as shown in Fig. 5, the throat 24 is not advanced sufficiently to trap the yarn against the shanks of the raised inactive needles.

While the invention has been shown and described in connection with needles having latches 29 used in a knitting machine having a rotary needle cylinder, it is to be understood the invention is equally applicable to other types of knitting machines using other types of needles.

What is claimed is:

1. A method of knitting comprising the feeding of two yarns to needles during relative reciprocating movements of the needles and their actuating cams, one of said yarns being fed to the last active needle during a relative rotary movement of said needles and cams at a substantial angle to the horizontal, the other of said yarns extending from said last active needle at a relatively small angle, and advancing sinkers to knock over stitches knitted of said one of said yarns, the throat of each sinker at the time of knocking over being in substantial alignment with the forward shank edge of an adjacent needle and advanced

at least as far as the knocking-over point of its associated needle.

2. A method of knitting at least two separate course yarns during reciprocating knitting comprising the separate knitting of the two yarns during each reciprocation, independently advancing the sinkers and thereby causing the sinker between the last active needle and the first inactive needle to knock the loop drawn of the first fed yarn over the hook of the last active needle as a loop of the second yarn fed is drawn by the last active needle during each reciprocating movement while causing said sinker to be advanced only to a position such that the sinker throat is in line with the forward edge of the adjacent inactive needle whereby a yarn engaged under the nebs of a number of sinkers associated with inactive needles following the active needles is kept free from rupturing and shearing.

3. In a knitting machine having independently operating needles, sinkers having nebs defining throats, actuating cams for said needles and sinkers comprising means for dividing the needles into groups of active and inactive needles, means for feeding two separate-course yarns to active needles during relative movements of the needles and their actuating cams and said sinker actuating cams advancing said sinkers to knock loops drawn of said first fed yarn over the tops of associated active needles as loops of the second fed yarn are drawn by said associated active needles with the sinker throats advancing only to the line of the forward edges of the needle shanks whereby a yarn engaged under the nebs of sinkers associated with inactive needles following the last active needle is kept free from rupturing and shearing.

4. In a knitting machine having independently movable needles and sinkers, said needles having forwardly bent hooks, actuating cams for said needles and sinkers comprising means for dividing the needles into active and inactive needles, and means for feeding two separate-course yarns to active needles during relative reciprocations of said needles and sinkers and their actuating cams, the sinkers and needles being so constructed and controlled in their movements as to cause the sinker associated with the last active needle during said given movements to knock the loops drawn of said first fed yarn over the hook of said last active needle as a loop of the second fed yarn is drawn by said last active needle, the said sinker at such time having the throat under its neb substantially at the line of the forward edge of the needle shank whereby a yarn engaged under the nebs of sinkers associated with a number of the first of the inactive needles during a given movement is kept free from rupturing and shearing.

5. In a knitting machine having independently operable needles and sinkers, said needles having forwardly bent hooks, actuating cams for said needles and sinkers comprising means for dividing the needles into active and inactive needles, and means for feeding two separate-course yarns to active needles during relative reciprocations of said needles and sinkers and their actuating cams, the forwardly bent hook of the last active needle causing the associated sinker to knock the loop drawn of the first fed yarn over the hook of said last active needle as a loop of the second fed yarn is drawn by said last active needle with the throat of said sinker advanced only to the forward edge of the shank of the adjacent inactive needle whereby a yarn engaged under the nebs of sinkers associated with inactive needles following the last

active needle in any given movement is kept free from rupturing and shearing.

6. A method of knitting at least two separate course yarns during rotary reciprocatory knitting comprising the separate knitting of the two yarns during each reciprocatory movement on less than the full complement of needles, independently advancing the sinkers and thereby causing the sinker between the last active needle and the first inactive needle to knock the loop drawn of the first yarn fed during each movement over the hook of the last active needle as a loop of the second fed yarn is drawn by said last active needle while causing said sinker to be advanced only to a position such that the sinker throat is in line with the forward edge of the adjacent inactive needle whereby the first yarn fed and which is engaged under the nebs of a number of sinkers associated with inactive needles following the active needles is kept free from rupturing and shearing.

7. In a knitting machine having independently operating needles, sinkers having nebs defining throats, actuating cams for said needles and sinkers comprising means for dividing the needles into groups of active and inactive needles during rotary reciprocatory knitting, means for feeding two separate-course yarns to active needles during relative movements of the needles and their actuating cams and said sinker actuating cams advancing said sinkers to knock the loops drawn of said first fed yarn over the tops of associated active needles as loops of the second fed yarn are drawn by said associated active needles with the sinker throats advancing only to the line of the forward edges of the needle shanks whereby the first fed yarn extending from the yarn feed to the last active needle and engaged under the nebs of sinkers associated with inactive needles following the last active needle is kept free from rupturing and shearing.

8. In a knitting machine having independently movable needles and sinkers, said needles having forwardly bent hooks, actuating cams for said

- needles and sinkers comprising means for dividing the needles into active and inactive needles, and means for feeding two separate-course yarns to active needles during relative rotary reciprocations of said needles and sinkers and their actuating cams, the sinkers and needles being so constructed and controlled in their movements as to cause the sinker associated with the last active needle during each reciprocatory movement to knock the loop drawn of said first fed yarn over the hook of said last active needle as a loop of the second fed yarn is drawn by said last active needle, the said sinker at such time having the thread under its nebs substantially at the line of the forward edge of the needle shank whereby said first fed yarn extending to said last active needle and engaged under the nebs of sinkers associated with a number of the first of the inactive needles during a given movement is kept free from rupturing and shearing.
9. In a knitting machine having independently operable needles and sinkers, said needles having forwardly bent hooks, actuating cams for said needles and sinkers, comprising means for dividing the needles into active and inactive needles, and means for feeding two separate-course yarns to active needles during relative rotary reciprocations of said needles and sinkers and their actuating cams, the forwardly bent hook of the last active needle causing the associated sinker to knock the loop drawn of the first fed yarn over the hook of said last active needle as a loop of the second fed yarn is drawn by said last active needle with the throat of said sinker advanced only to the forward edge of the shank of the adjacent inactive needle whereby the first fed yarn extending to said last active needle and engaged under the nebs of sinkers associated with inactive needles following the last active needle in any given reciprocatory movement is kept free from rupturing or shearing.

IVAN W. GROTHEY.
